UNITED STATES PATENT OFFICE

2,224,401

RAILWAY TRAFFIC CONTROLLING
APPARATUS

Charles H. Lay, Swissvale, Pa., assignor to The
Union Switch & Signal Company, Swissvale,
Pa., a corporation of Pennsylvania

Application May 11, 1940, Serial No. 334,609

12 Claims. (Cl. 246—3)

My invention relates to railway traffic controlling apparatus, and more particularly to apparatus for the remote control of railway traffic governing mechanisms.

Control of railway track switches and signals from a remote office station over line circuits extending between such office station and the location of the switches and signals is well known and in general use. In such control it is desirable to transmit over a single line circuit two or more different influences each of which effects a distinctive function in order to reduce the number of line circuits extending between the two locations since such locations may be spaced a relatively long distance apart and the provision of independent line circuits for each function is expensive. When two or more different influences are to be transmitted over a single line circuit, the current effecting such influences must be time spaced or of different characteristics in order to avoid interference and possible false operation.

Accordingly, a feature of my invention is the provision of novel and improved means for transmitting over a single two-wire line circuit two or more different currents time spaced to avoid interference.

Another feature of my invention is the provision of novel and improved apparatus of the type here contemplated wherewith some currents transmitted over a line circuit continue only long enough to insure that the desired function is initiated and the circuit is automatically conditioned for the transmission of another current and which other current may continue indefinitely until interrupted by some outside change of traffic or control conditions.

Again, a feature of the invention is the provision of novel and improved means for alternately transmitting control and return indication currents over a single two-wire line circuit.

Another feature of my invention is the provision of novel and improved apparatus for control of a track switch and its related signals from an office station, indication of the position of the track switch and signals at the office station and indication at such office station of the presence of a train in the vicinity of the track switch.

The above features, together with other advantages of my invention, I attain by providing two line relays one at a control office station and the other at a field station at which a mechanism to be controlled from the office station is located, connecting such relays at times in series in a

two-wire line circuit extending between the two stations and energizing the circuit by current supplied from a source at the field station. The line relay at the office station at least is a polarized relay and is selectively responsive to the polarity of the current supplied to this line circuit at the field station for governing an indication means located at the office station for indicating the condition of the controlled mechanism, the polarity of the current supplied to the line circuit being predetermined according to the condition of the controlled mechanism. This line circuit is so arranged that it can be interrupted at either station to deenergize the line relays and disconnect such relays from the line circuit. When the polarized line relay at the office station is deenergized, an office station current source can be connected to the line circuit to supply a control current thereto. The control current is supplied to the line circuit by use of the combination of a control relay and a repeater relay. For example, such circuit connection may include a back contact of a neutral control relay and a front contact of a slow release repeater relay with the result such circuit connection is completed and the control current has a duration equal to the slow release period of the repeater relay. The office station current source is capable of supplying current of either normal or reverse polarity and hence two different control functions can be effected by such control current. Subsequent to the release of the repeater relay, the office station polarized line relay is automatically reconnected to the line circuit for subsequent energization thereof by indication current supplied to the line circuit at the field station.

At the field station the control current is applied over a circuit connection including a back contact of the associated line relay to a controlling polarized relay whose polar contacts govern operating circuits of the mechanism to be controlled. This field station polarized relay is preferably characterized by its polar contact carrying armature remaining in the position to which it was last moved when the relay is deenergized, and hence it is necessary for the control current to have a duration only sufficient to position the polarized relay in order to effect an operation of the controlled mechanism although the time required to complete such operation may be relatively long and much longer than the duration of the control current. Which one of two operations of the controlled mechanism is effected is predetermined by the polarity of the

control current since the operating circuits of the controlled mechanism include polar contacts of the controlling polarized relay.

Contacts operated by the controlled mechanism when actuated to the position in agreement with the controlling polarized relay complete a local pick-up circuit for the field station line relay and this line relay on picking up completes at its own front contact a connection by which the field station line relay and current source are transferred from the local pick-up circuit to the line circuit to supply an indication current of a polarity predetermined by the position of the controlled mechanism. The return indication current hence energizes both line relays, and since the relay at the office station is a polarized relay, it is energized at a polarity corresponding to the polarity of the indication current and in turn in agreement with the position of the controlled mechanism.

Another slow acting relay is provided at the field station to delay the completion of the connection of the field station line relay and current source to the line circuit for the return transmission of the indication current, the delay period being predetermined and of sufficient duration to assure that the office station relays, that is, the control relay and its repeater relay, have had time to disconnect the office station current source and reconnect the office station polarized line relay to the line circuit.

I shall describe one form of apparatus embodying my invention and shall then point out the novel features thereof in claims.

The accompanying drawing is a diagrammatic view showing one form of apparatus embodying my invention when used for the control of a railway track switch and the signals associated therewith from an office station and for indication at the office station of the position of the track switch and the associated signals and the presence of a train in the vicinity of the track switch. It is to be understood of course that I do not wish to limit my invention to the control of a railway track switch and the associated wayside signals and this one use of apparatus embodying my invention serves to illustrate the many places where the invention is useful.

Referring to the drawing, the reference character 1T designates a railway track having a track switch SW leading to a second track 2T. The track rails are formed by the usual insulated rail joints with a detector track section TS which includes the track switch SW. The track section TS is provided with a track circuit including a source of current such as a battery 3 connected across the rails at one end of the section and a track relay TR connected across the rails at the other end of the section, the track circuit being extended to include the turnout rails in the usual and well-known manner.

In accordance with standard practice, four wayside signals R2A, R2B, L2A and L2B are associated with the track switch SW, signals R2A and R2B being mounted on a single mast and governing traffic moving from the left to the right as viewed in the drawing, and signals L2A and L2B governing traffic moving from right to left on tracks 1T and 2T, respectively. Additional signals would be preferably provided for governing traffic approaching the signals associated with track switch SW but such additional signals are not shown since they are not required for a full understanding of my invention and

would be in accordance with standard practice. Furthermore, the usual traffic controlled route locking, approach locking and other safety circuits for interconnecting the track switch and the associated signals would be provided but such circuits are also not shown for the sake of simplicity since they form no part of my invention and would be in accordance with standard practice.

The wayside signals R2A, R2B, L2A and L2B 10 may be of any of the well-known types and are shown conventionally.

The track switch SW is operated by a power switch machine SM. The type of switch machine is immaterial, and is shown by the symbol 15 commonly used to indicate a power switch machine. It is sufficient for the instant application to point out that switch machine SM would preferably include a reversible electric motor (not shown) which is operatively connected to 20 the track switch by a connection indicated by a dotted line 4, and which motor when supplied with current over a circuit including wire 5 is operated as required to move the track switch to its normal position, that is, the position shown in 25 the drawing, and when supplied with current over a circuit including wire 6, is operated as required to move the track switch to its reverse position, that is, the position opposite that shown in the drawing.

In addition to the usual traffic controlled circuits referred to hereinbefore for controlling the track switch and the related signals, the control of the switch machine SM and the wayside signals is effected from an office station such as a dispatcher's office DS through the medium of apparatus located partly at the office station DS and partly at a field station FS located adjacent the track switch and which apparatus embodies my invention. Each station DS and FS is provided with a suitable source of current such as a battery, a battery 7 being located at station DS and a battery 8 being located at station FS. That current of either normal or reverse polarity may be available, the batteries 7 and 8 are preferably of the type provided with a positive terminal B1, a negative terminal N1 and a mid or common terminal C. The voltages of the two half portions of each battery would be alike and the two batteries 7 and 8 would be preferably 50 of the same voltage.

Referring first to the apparatus at the field station FS, a controlling polarized relay WR is provided for governing the operating circuits of the switch machine SM, the arrangement being such that when relay WR is energized by current of normal polarity and its normal polar contact 9 is closed, current is supplied to a normal operating circuit including terminal B1 of battery 8, front contact 10 of track relay TR, normal polar contact 9 of relay WR, wire 5, motor of switch machine SM and wire 12 to battery terminal N1, and switch machine SM as explained hereinbefore is operated as required to move the track switch SW to its normal position. When 65 relay WR is energized by current of reverse polarity to close reverse polar contact 11 a reverse operating circuit is formed from terminal B1 over front contact 10 of relay TR, reverse polar contact 11 of relay WR, wire 6, motor of 70 switch machine SM and wire 12 to battery terminal N1, and the switch machine is operated as required to move the track switch to its reverse position. The polarized relay WR is preferably 75 of the type whose polar contact carrying arma-

ture remains in the position to which it was last moved when the relay is deenergized. Thus with relay WR energized for a period sufficient to close either polar contact 9 or 11, the corresponding 5 operation of switch machine SM is accomplished although relay WR may become deenergized before the operation of the switch machine is fully completed.

Before proceeding further with the description, 10 it should be pointed out that certain contact carrying fingers of the relays are shown remote from the windings of the relays in order to simplify the drawing. In each such case the contact finger is identified by the reference character 15 of the relay and is shown in the position corresponding to the normal position of the relay.

The apparatus at the field station FS includes 20 another traffic governing means in the form of four signal control relays, one for each of the four signals, and which signal control relays are identified by the reference character H plus a prefix corresponding to the reference character of the associated signal. The operating circuits of each signal are controlled by the respective 25 signal control relay. These signal operating circuits would be in accordance with usual practice and are here shown only to the extent required for a full understanding of my invention. As shown, the signal operating circuits are the same 30 for each signal and hence a description of the circuits for one signal will suffice for an understanding of all. Referring to signal R2A, when its signal control relay R2AH is deenergized and released closing back contact 13 an operating circuit easily traced is completed which causes signal 35 R2A to be operated to a stop position, and when relay R2AH is energized closing front contact 14 an easily traced circuit is completed by which signal R2A is operated to a proceed position.

40 A controlling polarized relay SR similar to polarized relay WR is provided at the field station for governing the signal control relays. When polarized relay SR is energized at normal polarity to close neutral front contact 15 and normal polar contact 16 and the track switch SW occupies its normal position, a circuit is formed from terminal B1 of battery 8 over front contact 17 of track relay TR, front contact 15 and normal polar contact 16 of relay SR, contact 18 of a switch circuit controller connected to the track switch as indicated by a dotted line and closed at the normal position of the track switch, winding of relay R2AH, a traffic controlled contact 19 and to terminal C of battery 8, and relay R2AH is energized and picked up to cause signal R2A to be operated to its proceed position. If track switch SW is set at its reverse position moving contact 18 of the switch circuit controller to the 45 position indicated by the dotted lines, then the circuit above traced is completed through the winding of signal control relay R2BH and traffic controlled contact 19 to battery terminal C, and relay R2BH is energized and picked up to cause signal R2B to be operated to its proceed position. When the track switch SW is set at its normal position and relay SR is energized at reverse polarity to close reverse polar contact 20, a circuit can be traced from battery terminal B1 over 50 front contact 17 of relay TR, front contact 15 and reverse polar contact 20 of relay SR, contact 21 of the switch circuit controller and closed at the normal position of the switch, winding of signal control relay L2AH, a traffic controlled contact 2 and to battery terminal C, and relay

L2AH is energized and picked up causing signal L2A to be operated to its proceed position. In the event track switch SW is set at its reverse position to cause contact 21 of the switch circuit controller to occupy the dotted line position the 5 last traced circuit is completed over winding of signal control relay L2BH and traffic controlled contact 2 to battery terminal C, and relay L2BH is energized and picked up causing signal L2B to be operated to its proceed position. It follows 10 that when the controlling polarized relay SR is energized at normal polarity, signal control relay R2AH or R2BH is selected according to the position of the track switch and the respective "right" signal R2A or R2B is operated to a proceed position, and when relay SR is energized at reverse polarity the signal control relay L2AH or L2BH is selected according to the position of the track switch and the respective "left" signal L2A or L2B is operated to a proceed position. The manner of energizing the controlling polarized relays WR and SR by control currents transmitted from the office station DS will be described hereinafter.

Referring to the apparatus at the office station DS, a switch lever L1 and a signal lever L2 are 25 mounted for convenient manual operation. The levers L1 and L2 may or may not be interlocked and preferably they are levers of a control machine without mechanical locking or electric lever locks. The switch lever L1 is operable either to 30 a left-hand or normal position N or to a right-hand or reverse position R for actuating four circuit controlling contacts 22, 23, 24 and 25. These circuit controlling contacts are illustrated in the usual conventional manner with the letter N or R 35 placed thereon to designate the position of lever L1 at which the contact is closed. Thus the letter N at contact 22 designates that contact 22 is closed at the normal position of lever L1.

The signal lever L2 is normally positioned at a 40 center or normal position N as illustrated in the drawing and is operable either to a left-hand LT or to a right-hand RT position for operating five circuit controlling contacts 26, 27, 28, 29 and 30 and which circuit controlling contacts are also 45 shown conventionally and provided with the letter N, RT or LT to designate the position of signal lever L2 at which the contact is closed.

A normal switch indication lamp NL, a reverse switch indication lamp RL and a track occupancy 50 lamp OS are disposed adjacent the switch lever L1 and are controlled by a polarized line relay 1R. When relay 1R is energized at normal polarity to close front neutral contact 31 and normal polar contact 32 the lamps NL and OS are 55 illuminated by current supplied from terminal B1 of battery 7 over front contact 31 of relay 1R, filament of lamp OS and wire 33 to terminal C of battery 7 for lamp OS, and over front contact 31 and normal polar contact 32 of relay 1R, 60 filament of lamp NL and wire 33 to terminal C for lamp NL. When relay 1R is energized at reverse polarity to close front contact 31 and reverse polar contact 34, the lamp OS is illuminated as before and lamp RL is illuminated by current 65 supplied over the circuit completed at reverse polar contact 34 as will be apparent from an inspection of the drawing. Two signal indication lamps LS and RS are disposed adjacent signal lever L2 and controlled by a polarized line relay 70 1S, the arrangement being such that when relay 1S is energized at normal polarity to close front neutral contact 35 and normal polar contact 36, a simple circuit is completed for lamp RS and when relay 1S is energized at reverse polarity 75

closing front contact 35 and reverse polar contact 37, a simple circuit is completed for lamp LS.

A two-wire line circuit including a line wire W1 and a common return line wire CL extending 5 between office station DS and field station FS is provided for the transmission of control current from the office station to the field station for energizing the switch controlling polarized relay WR in accordance with the position of switch lever 10 L1 and for the return transmission of indication current for the control of polarized line relay 1R in accordance with the position of the track switch and the occupancy of the track section TS. In like manner, a two-wire line circuit including 15 a line wire W2 and the common return line wire CL is provided for the transmission of control current from the office station to the field station for energizing the signal controlling polarized relay SR according to the position of signal lever 20 L2 and for the return transmission of indication current for controlling polarized line relay 1S in accordance with the position of the signals associated with switch SW. The common return wire CL is connected to the common terminal C 25 of both batteries 7 and 8 as will be readily apparent from an inspection of the drawing and serves as one side of each of the two line circuits.

Polarized line relay 1R is at times connected 30 to the line circuit including line wire W1 in series with a line relay 6R at the field station FS and when thus conditioned the line circuit permits the transmission of indication current from the field station to the office station, such indication current energizing relay 1R at either 35 normal or reverse polarity to govern the indication lamps NL, RL and OS as explained hereinbefore. The connection of relay 1R to line wire W1 is controlled by a neutral control relay 3R and a slow release repeater relay 4R, 40 this combination of relays 3R and 4R being also used to connect battery 7 to line wire W1 for supplying control current to line circuit W1—CL. Control of relays 3R and 4R is in turn effected by contacts 24 and 25 of switch 45 lever L1 through the medium of a polar relay 2R. Line relay 6R at the field station governs the connection of the switch controlling polarized relay WR and the battery 8 to the line circuit W1—CL. When relay 6R is deenergized 50 closing back contact 40, relay WR is connected across the line wires W1 and CL for energization of relay WR by control current supplied to the line circuit at the office station DS. When relay 6R is picked up to close its own front contact 41 the battery 8 and relay 6R are connected to the line circuit in a manner to be explained 55 when the operation of the apparatus is described, battery 8 supplying indication current of a polarity governed by the position of the track switch.

A slow release slow pick-up relay 5R is associated 60 with line relay 6R to delay the connection of battery 8 and line relay 6R to the line circuit W1—CL, the slow acting period of relay 65 5R being made great enough to assure sufficient time for the office station relays to automatically disconnect the office station current source and reconnect the line relay 1R to the line circuit subsequent to the transmission of a control current.

In like fashion the polarized line relay 1S associated with signal lever L2 is at times interposed in the line circuit including line wire W2 75 in series with a line relay 6S at the field station

for conditioning this line circuit for the transmission of indication current from the field station to the office station, such indication current energizing relay 1S at either normal or reverse polarity to control the indication lamps LS and RS in the manner previously explained. The connection of polarized line relay 1S to the line circuit W2—CL is governed by a neutral control relay 3S and a repeater relay 4S, the combination of relays 3S and 4S being also used to govern the connection of battery 7 to line circuit W1—CL for supplying control current to this line circuit. Control of relays 3S and 4S is in turn effected by contacts 28, 29 and 30 of signal lever L2. The line relay 6S at the field 15 station governs the connections of the signal controlling polarized relay SR and battery 8 to the line circuit W2—CL. When relay 6S is released closing back contact 63, the relay SR is connected across the line wires W2 and CL 20 for energization thereof by control current supplied to the line circuit at the office station. When line relay 6S is picked up to close its own front contact 80, the battery 8 and relay 6S are connected to the line circuit in a manner to 25 shortly appear for supplying indication current to the line circuit. A slow release relay 5S is associated with line relay 6S to delay the connection of battery 8 and relay 6S to the line circuit W2—CL for a predetermined interval subsequent to the transmission of a control current over this line circuit.

Having pointed out the different relays and apparatus embodying my invention, I shall next describe the operation thereof and in so doing 35 I shall assume that at the start the apparatus at both office station DS and field station FS occupies the position illustrated in the drawing. With switch lever L1 at its normal position N control relay 3R is retained energized by current supplied from terminal B1 of battery 7 over normal lever contact 24, normal polar contact 42 of relay 2R, winding of relay 3R and wire 33 to terminal C of battery 7. Repeater relay 4R is in turn energized over a simple circuit including front contact 43 or relay 3R. With both relays 3R and 4R picked up to close front contacts 49 and 48, respectively, polarized line relay 1R is connected to the line circuit W1—CL, and since line relay 6R at the field 50 station is normally picked up in a manner to later appear, indication current is supplied to the line circuit from battery 8, the polarity of such indication current being of normal polarity in agreement with the normal position of 55 track switch SW. The circuit for the transmission of this indication current can be traced from terminal B1 of battery 8 over contact 44 of the switch circuit controller and closed at the 60 normal position of switch SW, normal polar contact 45 of relay WR, winding of line relay 6R, back contact 46 of relay 5R, front contact 41 of relay 6R, front contact 47 of track relay TR, line wire W1 to station DS, front contact 48 65 of relay 4R, front contact 49 of relay 3R, winding of relay 1R, wire 33 to terminal C at office station DS and common return wire CL to terminal C of battery 8 at field station FS. This indication current is of normal polarity and relay 1R is energized at normal polarity to close front contact 31 and normal polar contact 32 so that normal switch indication lamp NP is illuminated to indicate the normal position of track switch SW and lamp OS is illuminated to 75

indicate that the track section TS is unoccupied and track relay TR is picked up to close front contact 41.

In the event the operator at office station DS 5 desires to move the track switch SW to its reverse position, the switch lever L1 is moved to its reverse position R. The opening of normal lever contact 24 deenergizes control relay 3R and that relay is deenergized and released immediately 10 to open front contact 49 and interrupt the line circuit so that both line relays 1R and 6R are deenergized and released. With relay 3R released to open front contact 43, the repeater relay 4R is deenergized but is not released until the 15 end of its slow release period. During the interval relay 3R is released and repeater relay 4R is picked up, a control current is supplied to the line circuit W1—CL to energize the switch controlling polarized relay WR. This circuit can be 20 traced from terminal N1 of battery 1, over reverse lever contact 23, back contact 50 of relay 1R, back contact 51 of relay 3R, front contact 48 of relay 4R, line wire W1 to field station FS, front contact 47 of track relay TR, back contact 40 25 of relay 6R, winding of relay WR and line wire CL back to terminal C of battery 1. This control current is of reverse polarity and relay WR is energized at reverse polarity to close its reverse polar contact 11 so that switch machine SM is 30 operated as required to move the track switch SW to its reverse position. When repeater relay 4R is released at the end of its slow release period to open front contact 48 the control current is interrupted but relay WR remains at its reverse 35 position closing reverse polar contact 11 after the control current ceases due to the characteristics of the relay. When repeater relay 4R is released to close back contact 52, current flows from terminal B1 of battery 1 over reverse lever contact 25, lower winding 53 of polar relay 2R and back contact 52 of relay 4R to terminal C of battery 1, and polar relay 2R is energized as required to 40 close its reverse polar contact 54. The closing of reverse polar contact 54 of relay 2R completes a 45 circuit for reenergizing relay 3R, the circuit including terminal B1 of battery 1, lever contact 25, reverse polar contact 54 of relay 2R, winding of relay 3R and wire 33 to terminal C. When relay 3R picks up to close front contact 49 repeater 50 relay 4R is reenergized and picked up and with both relays 3R and 4R picked up to close front contacts 49 and 48, respectively, the polarized line relay 1R is again connected to the line circuit W1—CL.

At the field station, the release of line relay 1R to close back contact 55 completes a circuit from terminal B1 of battery 8 over front contact 56 of track relay TR, back contact 55 of relay 6R and winding of relay 5R to terminal C, and relay 5R is energized and picked up at the end of its slow pick-up period. When relay 5R is picked up to close front contact 57, a local pick-up circuit for relay 6R is prepared so that when track relay SW is operated to its reverse position 55 in agreement with the reverse position of relay WR and contact 58 of the switch circuit controlled is moved to the dotted line position, a pick-up circuit for relay 6R is completed by which current flows from terminal C of battery 8 over resistor 59, front contact 57 of relay 5R, winding of relay 6R, reverse polar contact 60 of relay WR, contact 58 of the switch circuit controller and to terminal N1 of battery 8, and relay 6R is picked up. Relay 6R on being picked up to open back contact 55 deenergizes relay 5R and relay 5R is deenergized

and released at the end of its slow release period. Relay 6R on picking up to close front contact 41 prepares a connection to the line circuit so that when relay 5R is released to close back contact 46, relay 6R and battery 8 are transferred from the local pick-up circuit to the line circuit W1—CL for supplying an indication current thereto. The circuit for this indication current involves terminal C of battery 8, line wire CL to terminal C of office station DS, wire 33, winding of relay 10 1R, front contacts 49 and 48 of relays 3R and 4R, respectively, line wire W1 to station FS, front contact 47 of track relay TR, front contact 41 of line relay 6R, back contact 46 of relay 5R, winding of relay 6R, reverse polar contact 60 of relay 15 WR and contact 58 of the switch circuit controller to terminal N1 of battery 8. This return indication current is of reverse polarity and line relay 1R at the office station is energized at reverse polarity causing reverse switch indication lamp 20 RL to be illuminated to indicate the reverse position of the track switch, lamp OS being also illuminated as before to indicate that track section TS is unoccupied and track relay TR is picked up.

It is to be pointed out that repeater relay 4R 25 is provided with a slow release period sufficiently long that operation of the polarized relay WR by the control current is assured. Since the circuit of relay 5R is closed when relay 6R is released to connect polarized relay WR to the line circuit, 30 the slow pick-up period of relay 5R is made sufficiently long to assure that relay WR is operated to its reverse position to open normal polar contact 45 before relay 5R is picked up to close its front contact 57 with the result that reenergization of line relay 6R by current supplied over the normal polar contact 45 of relay WR is avoided and that line relay 6R can be reenergized only when its pickup circuit is completed in response to the track switch SW being moved to the reverse position in agreement with the reverse position of relay WR. The slow release period of relay 5R is made sufficiently long to assure that when relay 6R is picked up and relay 5R is deenergized, the relay 5R is not released to close 45 back contact 46 and complete the connection of line relay 6R and battery 8 to the line circuit until after the relays 3R and 4R at the office station have had time to disconnect battery 7 from the line circuit and reconnect the polarized line 50 relay 1R thereto. Line relay 6R is slightly slow releasing to bridge the interval relay 5R is in transit between its front contact 57 and back contact 46.

To restore the track switch SW to its normal position, switch lever L1 is moved back to its normal position N. The opening of reverse lever contact 25 causes control relay 3R to be deenergized and immediately released to interrupt the line circuit and cause line relays 1R and 6R to be 60 deenergized and released. Repeater relay 4R is also deenergized when control relay 3R is released but relay 4R does not release until the end of its slow release period and during the period relay 3R is released to close back contact 51 and relay 65 4R is picked up to close front contact 48 a control current is supplied to the line circuit for energizing polarized relay WR. This control current flows from terminal B1 of battery 1 over normal lever contact 22, back contact 50 of relay 70 1R, back contact 51 of relay 3R, front contact 48 of relay 4R, line wire W1, front contact 47 of relay TR, back contact 40 of relay 6R, winding of relay WR and common return wire CL to terminal C of battery 1, and relay WR is energized at nor- 75

mal polarity to close its normal polar contact 9 and cause switch machine SM to be operated as required to move the track switch to its normal position. Again it is to be noted that the control 5 current has a duration equal to the slow release period of repeater relay 4R but that relay WR remains at its normal position after the control current ceases due to the characteristic of the relay. The closing of normal contact 24 of lever 10 L1 supplies current to polar relay 2R from terminal B1 of battery 7 over lever contact 24, top winding 62 of relay 2R and back contact 52 of relay 4R to terminal C of battery 7, and relay 2R is energized at normal polarity to close its normal 15 pole contact 42 so that the relay 3R is reenergized over the circuit including lever contact 24 and normal polar contact 42. Relay 3R on picking up reenergizes repeater relay 4R and that relay on picking up to close contact 48 completes 20 the connection of line relay 1R to the line circuit. At the field station the release of line relay 6R to close back contact 55 energizing relay 5R which relay on picking up to close front contact 57 prepares the pick-up circuit for line relay 6R so that 25 when the track switch is operated to its normal position in agreement with the normal position of relay WR current is supplied to the pick-up circuit of relay 6R from terminal B1 of battery 8 over contact 44 of the switch circuit controller, 30 normal polar contact 45 of relay WR, winding of relay 6R, front contact 57 of relay 5R, resistor 59 and to terminal C of battery 8. When line relay 6R is picked up over this pick-up circuit to open back contact 55, relay 5R is deenergized and 35 releases at the end of its slow release period to complete the connection of battery 8 through line relay 6R to the line circuit and indication current flows from terminal B1 of battery 8 over contact 44 of the switch circuit controller and the 40 circuit previously traced by which line relay 1R at the office station is energized at normal polarity in series with relay 6R. Energization of relay 1R at normal polarity causes the display of the normal switch indication lamp NL and track occupancy indication lamp OS in the manner described hereinbefore.

It should be observed that in the event switch lever L1 is moved to its reverse position and control current is transmitted from the office station 50 for energizing controlling relay WR at reverse polarity and the switch machine fails to move the track switch to the corresponding reverse position, the operation of the switch lever L1 back to its normal position will cause a transmission of 55 control current of normal polarity to energize relay WR at its normal polarity and bring this relay into agreement with the position of the track switch since relays 3R and 4R are reenergized subsequent to the transmission of the control current independent of the apparatus at the field station.

Again, it should be observed, that when a train occupies track section TS to shunt track relay TR the line circuit is opened at front contact 47 of 60 relay TR with the result that line relay 1R and line relay 6R are both deenergized and that when line relay 1R is deenergized both lamps NL and OS are extinguished to indicate that the track section TS is occupied and that the track switch 65 cannot be controlled at the office station. When the train vacates section TS and relay TR is picked up to close front contacts 47 and 56, relay 5R is picked up to complete the local pick-up circuit for relay 6R and relay 6R on picking up 70 closes front contact 41 to prepare the connection

to the line circuit and opens back contact 55 to cause relay 5R to be released, so that when back contact 46 of relay 5R is again closed the line circuit is again reestablished for the transmission of the return indication current. 5

From the foregoing description of the operation of the apparatus associated with switch lever L1, it is clear that with lever L1 at either its normal or reverse position relays 3R and 4R are picked up and line relays 1R and 6R are interposed in 10 series in the line circuit for the transmission of indication current from the field station, the polarity of the current being predetermined according to the position of the track switch and the transmission of which indication current will 15 continue indefinitely. When lever L1 is moved from one position to the other relays 3R and 4R are operated sequentially and control current is transmitted during the release period of repeater relay 4R to bring about energization of controlling relay WR at a polarity predetermined according to the position of switch lever L1. When switch SW is operated to the position in agreement with controlling relay WR, a local pick-up circuit for line relay 6R is completed and when 20 relay 6R is picked up it reestablishes a line circuit for the transmission of a return indication current. It is also clear that slow acting relay 5R delays the reestablishing of the line circuit 25 for the transmission of the return indication current for a predetermined period which is great enough to assure that the relays 3R and 4R have time to release sequentially and then to be reenergized and reconnect line relay 1R to the line 30 circuit. 35

In taking up the operation of the apparatus associated with signal lever L2 for controlling the wayside signals, it is to be noted that since signal lever L2 normally occupies a center position N for which all signals are at a stop position, the control of relay 3S and its repeater relay 4S is preferably modified from that provided for relay 3R and its repeater relay 4R associated with switch lever L1, to the extent that relays 3S and 4S are retained energized until the transmitted control 45 current completes its designated function at the field station at which time the line circuit is preferably interrupted by operation of the relays at the field station and relays 4S and 3S are then caused to function to disconnect the current 50 source at the office station from the associated line circuit and to connect the line relay 1S to the line circuit. Also at the field station, the slow release relay 5S is normally energized with the result that the line relay 6S is normally deenergized to connect the controlling polarized relay SR to the line circuit and to disconnect the current source 8 from the line circuit. When signal lever L2 is at its normal center position N to close normal contact 30, a simple circuit is completed 60 for repeater relay 4S and relay 4S is picked up. At the field station slow release relay 5S is normally energized by current supplied over a circuit including terminal B1 of battery 8, back contacts 65 64, 65, 66, 67 and 68 of relays R2AH, R2BH, L2AH, L2BH and 6S, respectively, winding of relay 5S and terminal C.

In the event it is desired to operate either one of the "right" signals R2A or R2B to permit a train to move over the track switch, signal lever 70 L2 is moved to its right-hand position RT. When lever contact 30 is opened, the repeater relay 4S is deenergized, but relay 4S is retained picked up for a period due to its slow release characteristic. The closing of lever contact 28 at the 75

RT position completes a circuit over which a signal control current flows from terminal B1 of battery 7, through lever contact 28, winding of relay 3S, front contact 69 of repeater relay 4S, line wire W2, back contact 63 of relay 6S, winding of polarized relay SR and common return wire CL to terminal C of battery 7. This control current is effective to energize and pick up relay 3S and to energize relay SR at normal polarity. The picking up of relay 3S to close front contact 70 completes a second circuit by which the repeater relay 4S is retained energized as long as the control current continues. The energizing of relay SR at normal polarity to close front contact 15 and normal polar contact 16 completes the previously traced circuit for either relay R2AH or R2BH depending upon the position of the track switch SW and either signal R2A or R2B is operated to a proceed position. When signal control relay R2AH or R2BH is picked up to open either back contact 64 or 65, the slow release relay 5S is deenergized and released at the end of its slow release period. During the interval that either relay R2AH or R2BH is picked up to close either front contact 71 or 72 and relay 5S is picked up to close its front contact 74, a pick-up circuit for line relay 6S is completed over which current flows from terminal B1 of battery 8, through either front contact 71 or 72, normal polar contact 73 of relay SR, winding of relay 6S, front contact 74 of relay 5S, resistor 75 and to terminal C of battery 8. With line relay 6S picked up due to the above traced pick-up circuit to open back contact 63 the line circuit is interrupted and the control current ceases. This causes relay 3S at the office station and relay SR at the field station to be deenergized and immediately released, the normal polar contact of relay SR remaining closed however, due to the characteristic of relay SR. The closing of front contact 16 of relay 6S completes a shunt path around front contact 15 of relay SR so that the circuit of the signal control relay R2AH or R2BH is still complete after relay SR is deenergized. At the office station, the opening of front contact 70 of relay 3S deenergizes repeater relay 4S and relay 4S releases at the end of its slow release period to close back contact 77 and complete a connection by which line relay 1S is connected to the line circuit. The slow release period of repeater relay 4S need be only long enough to bridge the interval between the opening of lever contact 30 and the closing of front contact 70 of relay 3S subsequent to the movement of the signal lever. At the field station, relay 5S is provided with a slow release period somewhat greater than the slow release period of relay 4S at the office station, so that when relay 5S is released to close back contact 78 and transfer battery 8 and line relay 6S to the line circuit battery 7 has been disconnected from the line circuit and an indication current flows from terminal B1 of battery 8 over either front contact 71 or 72 of relay R2AH or R2BH, normal polar contact 73 of relay SR, winding of relay 6S, back contact 78 of relay 5S, front contact 80 of line relay 6S, line wire W2, back contact 77 of relay 4S, winding of relay 1S, lever contact 26, wire 33 to terminal C at the office station and line wire CL to terminal C of battery 8 at the field station. Line relay 6S is now retained energized in series with the line relay 1S by the indication current, relay 1S being energized at normal polarity to cause indication lamp RS to be illuminated to

indicate that relay R2AH or R2BH has been picked up to operate the respective "right" signal R2A or R2B to a proceed position.

It follows that a control current is supplied from battery 7 at the office station to the line circuit W2-CL just long enough to cause operation of polarized relay SR and the picking up of the signal control relay. When the selected signal control relay is picked up a local pick-up circuit is formed for line relay 6S during the slow release period of the relay 5S and relay 6S on picking up opens the line circuit and interrupts the control current. Subsequent to the interruption of the control current, control relay 3S and repeater relay 4S are operated to disconnect the battery 7 of the office station from the line circuit and to connect the line relay 1S thereto. When slow acting relay 5S is released battery 8 and line relay 6S are transferred from the local pick-up circuit to the line circuit and an indication current is supplied to the line circuit which energizes relays 6S and 1S in series and causes a corresponding indication lamp to be illuminated, and which indication current may continue until the circuit is changed either by a movement of the signal lever or by traffic conditions in the vicinity of the track switch. In the event a train moves past signal R2A or R2B into track section TS to shunt track relay TR, the release of relay TR to open front contact 17 deenergizes the selected signal control relay R2AH or R2BH and that relay upon releasing causes the associated signal to be operated to its stop position. Also the line circuit is interrupted at either front contact 71 or 72 of the signal control relay and the transmission of the indication current is discontinued with the result that both line relays 1S and 6S are deenergized and released, the release of relay 1S causing lamp RS to be extinguished to indicate the stop position of the signal. Release of line relay 6S at the field station to close back contact 63 completes the circuit for relay 5S and that relay is picked up with the result that when the train vacates track section TS and track relay TR is re-energized, the signal control relay R2AH or R2BH cannot be again energized until a new control current for energizing relay SR to close its front contact 15 is transmitted from the office station.

In the event signal lever L2 is restored to its normal position N subsequent to the extinguishing of the indication lamp RS, the closing of lever contact 30 reenergizes repeater relay 4S after which a new signal control current may be transmitted for energizing relay SR by moving lever L2 again to its RT position.

The operation of the apparatus for the control of a "left" signal L2A or L2B in response to a movement of signal lever L2 to its LT position is similar to that described in detail in connection with operation of lever L2 to its RT position for controlling signal R2A or R2B and the description need not be repeated except to point out that when lever L2 is moved to its LT position contact 29 connects the line circuit W2-CL to terminal N1 of battery 7 and the control current is of reverse polarity so that relay SR is energized at reverse polarity to select either signal control relay L2AH or L2BH. Also with relay SR energized at reverse polarity the closing of reverse polar contact 83 and the closing of either front contact 81 or 82 of relay L2AH or L2BH, connects terminal N1 of battery 8 to the pick-up circuit of line relay 6S so that when

relay 5S is released to transfer battery 8 and line relay 6S to the line circuit the return indication current is of reverse polarity with the result that relay 1S is energized at reverse polarity to cause lamp LS to be illuminated to indicate that a "left" signal has been operated to a proceed position.

Although I have herein shown and described only one form of railway traffic controlling apparatus embodying my invention, it is understood that various changes and modifications may be made therein within the scope of the appended claims without departing from the spirit and scope of my invention.

15. Having thus described my invention, what I claim is:

1. In railway traffic controlling apparatus for use with a two-wire line circuit extending between a first and a second station and a current source at each station for the exchange of control and indication influence between the two stations, the combination comprising, a line relay at each station, a manually operable lever at said first station, a controlling relay at said second station to govern the operation of a controlled mechanism, means including a contact governed by said lever and a back contact of the line relay at said second station to connect the current source of said first station and said controlling relay to the line circuit for transmitting a control influence from the first to the second station to cause operation of said controlled mechanism, automatic means initiated by movement of the lever to terminate said control influence and subsequently connect the line relay at the first station to the line circuit, a local pick-up circuit including a contact governed by said controlled mechanism to connect the line relay of the second station to the current source of that station to pick up that line relay, and circuit means including a front contact of the line relay at the second station and a contact governed by said controlled mechanism to connect the current source and the line relay at the second station to the line circuit in series with the line relay at the first station for transmitting an indication influence from the second to the first station.

2. In railway traffic controlling apparatus for use with a two-wire line circuit extending between a first and a second station and a current source at each station for the exchange of control and indication influence between the two stations, the combination comprising, a line relay at each station, a manually operable lever at said first station, a controlling relay at said second station to govern the operation of a controlled mechanism, means including a contact governed by said lever and a back contact of the line relay at said second station to connect the current source of said first station and said controlling relay to the line circuit for transmitting a control influence from the first to the second station to cause operation of said controlled mechanism, automatic means initiated by movement of the lever to terminate said control influence and subsequently connect the line relay at the first station to the line circuit, a local pick-up circuit including a contact governed by said controlled mechanism to connect the line relay of the second station to the current source of that station to pick up that line relay, circuit means including a front contact of the line relay at the second station and a contact governed by said controlled mechanism to connect

the current source and the line relay at the second station to the line circuit in series with the line relay at the first station for transmitting an indication influence from the second to the first station, and a slow release relay at the second station energized over a back contact of the line relay at the second station and having a back contact interposed in said circuit means to delay for a predetermined period the transmission of such indication influence.

3. In railway traffic controlling apparatus for use with a two-wire line circuit extending between a first and a second station and a current source at each station for the exchange of control and indication influences between the two stations, the combination comprising, a line relay at each station, a manually operable lever at said first station, a controlling relay at said second station to govern the operation of a controlled mechanism, an indicator controlled over a contact of the line relay at said first station, a slow release repeater relay controlled by a contact of said lever; means including another contact of said lever, a front contact of said repeater relay and a back contact of the line relay at the second station to connect the current source at said first station and said controlling relay to the line circuit for transmitting a control influence from the first to the second station to cause operation of said controlled mechanism; automatic means including contacts of said repeater relay to disconnect the current source of the first station from the line circuit and to connect the line relay of that station thereto, a slow release relay at said second station energized over a back contact of the line relay at that station, a local pick-up circuit including a contact governed by said controlled mechanism and a front contact of said slow release relay to connect the line relay at the second station to the current source of that station to pick up that line relay; and means including a front contact of the line relay at the second station, a back contact of the slow release relay at that station and a contact governed by said controlled mechanism to connect the current source and line relay at the second station to the line circuit in series with the line relay at the first station for transmitting an indication influence from the second to the first station to effect a control of said indicator.

4. In railway traffic controlling apparatus for use with a two-wire line circuit extending between a first and a second station and a current source at each station for the exchange of control and indication influences between the two stations, the combination comprising, a line relay at each station, a manually operable lever at said first station, a controlling relay at said second station to govern the operation of a controlled mechanism, an indicator governed over a contact of the line relay at the first station, a slow release repeater relay at the first station normally energized over a contact governed by said lever; means including another contact governed by said lever, a front contact of said repeater relay and a back contact of the line relay at the second station to connect the first station current source and said controlling relay to the line circuit to energize the controlling relay by control current transmitted from the first station during the slow release period of said repeater relay to effect an operation of said controlled mechanism; automatic means controlled over a back contact of the repeater relay to

- connect the first station line relay to the line circuit, another slow release relay at the second station energized over a back contact of the line relay at that station, a local pick-up circuit including a contact governed by said controlled mechanism and a front contact of said other slow release relay to energize the second station line relay from the second station current source; and means including said contact governed by the controlled mechanism, a back contact of said other slow release relay and a front contact of the second station line relay to transfer the second station line relay and current source to the line circuit to energize said two line relays in series by indication current transmitted from the second station to effect a control of said indicator.
5. In railway traffic controlling apparatus for use with a two-wire line circuit extending between a first and a second station and a current source at each station for the exchange of control and indication influences between the two stations, the combination comprising, a manually operable lever having a first and a second position located at the first station, a polarized controlling relay at the second station to govern a controlled means to either a first or a second position, indication means having a first and a second condition located at the first station, a polarized line relay at the first station to govern said indication means, another line relay at the second station, means including either a first or a second position contact of said lever and a back contact of said other line relay to connect the first station current source and said polarized controlling relay to the line circuit to energize said controlling relay at normal or reverse polarity according to the position of the lever to effect a corresponding position of the controlled means, automatic means controlled by said lever effective to disconnect the first station current source from the line circuit and connect said polarized line relay thereto subsequent to a movement of the lever, a local pick-up circuit including either a first position contact of said controlled means and a normal polar contact of said controlling relay or a second position contact of the controlled means and a reverse polar contact of the controlling relay to energize said other line relay, and means including a front contact of said other line relay and a first or a second position contact of said controlled means to connect the second station current source to the line circuit to energize said polarized line relay at normal or reverse polarity according to the position of the controlled means to effect a corresponding condition of said induction means.
6. In railway traffic controlling apparatus for use with a two-wire line circuit extending between a first and a second station and a current source at each station for the exchange of control and indication influences between the two stations, the combination comprising, a line relay at each station, a manually operable lever at the first station, a normally deenergized controlling relay at the second station, a control relay and a slow release repeater relay at the first station, means including a contact of said lever to energize said control relay and in turn said repeater relay; means including a front contact of said control relay, a front contact of said repeater relay, a front contact of the second station line relay and a contact governed by said controlling relay to connect said two line
- relays and the current source at the second station in series in the line circuit for transmitting an indication influence from the second to the first station and which may continue indefinitely; means including a back contact of said control relay, a front contact of said repeater relay and a back contact of the second station line relay to connect the first station current source and said controlling relay to the line circuit for transmitting a control influence from the first to the second station when the lever is moved and which influence continues for the slow release period of the repeater relay, automatic means controlled over a back contact of the repeater relay to reenergize said control relay, and a pick-up circuit including a contact governed by said controlling relay in response to the control influence to connect the second station line relay to the current source at that station to pick up that line relay and reestablish the line circuit with the two line relays in series for transmitting a new indication influence from the second to the first station.
7. In railway traffic controlling apparatus for use with a two-wire line circuit extending between a first and a second station and a current source at each station for the exchange of control and indication influences between the two stations, the combination comprising, a line relay at each station, a manually operable lever at the first station, a normally deenergized controlling relay at the second station, a control relay and a slow release repeater relay at the first station, means including a contact of said lever to energize said control relay and in turn said repeater relay; means including a front contact of said control relay, a front contact of said repeater relay, a front contact of the second station line relay and a contact governed by said controlling relay to connect said two line
- relays and the current source at the second station in series in the line circuit for transmitting an indication influence from the second to the first station and which may continue indefinitely; means including a back contact of said control relay, a front contact of said repeater relay and a back contact of the second station line relay to connect the first station current source and said controlling relay to the line circuit for transmitting a control influence from the first to the second station when the lever is moved and which influence continues for the slow release period of the repeater relay, automatic means controlled over a back contact of the repeater relay to reenergize said control relay, a pick-up circuit including a contact governed by said controlling relay in response to the control influence to connect the second station line relay to the current source at that station to pick up that line relay and reestablish the line circuit with the two line relays in series for transmitting a new indication influence from the second to the first station, and a slow release relay at the second station energized over a back contact of the line relay at the same station and having a back contact interposed in the connection of the second station current source to the line circuit to delay the transmission of the indication influence for a period.
8. In railway traffic controlling apparatus for use with a two-wire line circuit extending between an office station and a track switch for governing the track switch to its normal and reverse positions in agreement with the normal and reverse positions of a switch lever at the

- office station and for governing a normal and a reverse indicator at the office station in agreement with the position of the track switch, the combination comprising, a polarized line relay 5 at the office station for controlling said indicators, a polarized switch controlling relay at the switch, a control relay and a slow release repeater relay at the office station, means including either a normal or a reverse lever contact to energize said control relay and said repeater relay, another line relay at said switch, means including a back contact of said other line relay to connect said polarized controlling relay to said line circuit, means including either a normal or 10 a reverse lever contact together with a back contact of said control relay and a front contact of said repeater relay to supply control current of normal or reverse polarity to the line circuit to energize said controlling relay according to the 15 position of the lever to effect a corresponding position of the switch, means including a back contact of said repeater relay to reenergize said control relay and in turn the repeater relay, means including a front contact of the control relay and 20 a front contact of the repeater relay to connect said polarized line relay to the line circuit, a pick-up circuit including a normal position switch contact and a normal polar contact of the controlling relay or a reverse position switch contact and a reverse polar contact of the controlling relay to pick up said other line relay, and circuit means including a front contact of said other line relay and said switch contacts to supply indication 25 current of normal or reverse polarity to the line circuit to energize said polarized line relay to control the corresponding indicator.
9. In railway traffic controlling apparatus for use with a two-wire line circuit extending between an office station and a track switch for governing the track switch to its normal and reverse positions in agreement with the normal and reverse positions of a switch lever at the office station and for governing a normal and a reverse indicator at the office station in agreement with 40 the position of the track switch, the combination comprising, a polarized line relay at the office station for controlling said indicators, another line relay at the track switch, a polarized switch controlling relay connected to said line circuit 45 over a back contact of said other line relay, a control relay and an associated slow release repeater relay at the office station, means including either a normal or a reverse lever contact to energize said control relay to cause said control relay and its repeater relay to be sequentially released when the lever is moved from one position to the other, means including a normal and a reverse lever contact together with a back contact of said control relay and a front contact of said repeater relay to supply control current of normal or reverse polarity according to the position 50 of the lever to the line circuit to correspondingly energize said switch controlling relay, means including a back contact of the repeater relay to reenergize said control relay, means including a front contact of said control relay and a front contact of the repeater relay to connect said polarized line relay to the line circuit, another 55 slow release relay energized over a back contact of said other line relay, a local pick-up circuit including either a normal switch contact and a normal polar switch controlling relay contact or a reverse switch contact and a reverse polar 60 switch controlling relay contact and controlled 65

over a front contact of said other slow release relay to energize said other line relay, means including a back contact of said other slow release relay and a front contact of said other line relay to transfer such pick-up circuit to said line circuit to supply indication current of normal or reverse polarity according to the position of the switch to correspondingly energize said polarized line relay. 5

10. In railway traffic controlling apparatus for use with a two-wire line circuit extending between an office station and a track section for controlling a right and a left signal at the track section from a signal lever at the office station and indicating at such lever the condition of the signals, the combination comprising, a polarized line relay at the office station for selectively governing a right and a left signal indicator, another line relay at the track section, a polarized signal controlling relay for selectively governing said signals and connected to said line circuit over a back contact of said other line relay, a control relay and an associated repeater relay at the office station and said repeater relay energized over either a normal position contact of said signal lever or a front contact of said control relay, means including either a right or a left position contact of said lever to supply current of normal or reverse polarity to the line circuit through the winding of said control relay to energize the control relay and correspondingly energize said signal controlling relay, a slow release relay energized over a back contact of said other line relay, a pick-up circuit including either a normal or a reverse polar contact of said signal controlling relay and a front contact of said slow release relay to pick up said other line relay to interrupt the control current and cause the sequential release of the control and repeater relays, means including a back contact of the repeater relay to connect said polarized line relay to the line circuit, and means including a back contact of said slow release relay and a front contact of said other line relay to transfer said pick-up circuit to the line circuit to supply indication current of normal or reverse polarity according to the position of the signal controlling relay to correspondingly energize said polarized line relay. 25

11. In railway traffic controlling apparatus, the combination comprising, a two-wire line circuit extending between an office station and a field station, a current source at each station, a control lever at the office station operable to a first and a second position, indication means at the office station having a first and a second condition, a traffic controlling mechanism at the field station having a first and a second position, a polarized controlling relay at the field station for selectively governing the positions of said mechanism, a polarized line relay at the office station for selectively governing the conditions of said indication means, another line relay at said field station, a slow release relay at the office station, means including a contact governed by said lever and closed in response to either position of the lever to energize said slow release relay and operative to deenergize that relay and subsequently reenergize the relay when the lever is moved from one position to the other, means including a front contact of said slow release relay and a back contact of said other line relay to connect the office station current source and said controlling polarized relay to said line circuit to supply cur- 75

- rent of normal or reverse polarity to said controlling relay according to the position of the lever during the slow release period of said slow release relay for governing said mechanism, a pick-up 5 circuit including a contact governed by said mechanism to pick up said other line relay, and means including a front contact of said other line relay and a front contact of said slow release relay to connect said two line relays and said 10 field station current source in series in said line circuit to supply current of either normal or reverse polarity according to the position of the mechanism to energize said polarized line relay for governing the indication means.
- 15 12. In railway traffic controlling apparatus, the combination comprising, a two-wire line circuit extending between an office station and a field station, a current source at each station, a control lever at the office station operable to a first 20 and a second position, indication means at the office station having a first and a second condition, a traffic controlling mechanism at the field station having a first and a second position, a polarized controlling relay at the field station for 25 selectively governing the positions of said mechanism, a polarized line relay at the office station for selectively governing the conditions of said indicating means, another line relay at said field station, a polar relay and a control relay and a 30 slow release repeater relay at the office station; means including a first or a second position lever

contact and a back contact of said repeater relay to energize said polar relay at normal or reverse polarity, means including a first position lever contact and a normal contact of said polar relay or a second position lever contact and a reverse contact of the polar relay to energize said control relay, means including a front contact of the control relay to energize said repeater relay, means including a back contact of said control relay, a front contact of said repeater relay, a 15 back contact of said other line relay and either a first or a second position lever contact to connect said office station current source and said controlling polarized relay to said line circuit to energize that polarized relay at a polarity pre-determined by the position of the lever, a pick-up circuit including either a first position contact of said mechanism and a normal polar contact of said controlling relay or a second position contact of said mechanism and a reverse 20 polar contact of said controlling relay to pick up said other line relay, and means including a front contact of said control relay, a front contact of said other line relay and either a first or a second position contact of said mechanism to connect 25 said two line relays and the field station current source in series to said line circuit to energize said polarized line relay at a polarity predetermined by the position of said mechanism.

CHARLES H. LAY. 30
